UNITED STATES PATENT OFFICE.

MOSES L. HAWKS, OF NEW YORK, N. Y.

GAME.

1,150,517.

Specification of Letters Patent. Patented Aug. 17, 1915.

Application filed June 23, 1914. Serial No. 846,724.

To all whom it may concern:

Be it known that I, MOSES L. HAWKS, a citizen of the United States, and a resident of New York city, in the county of New York 5 and State of New York, have invented certain new and useful Improvements in Games, of which the following is a specification.

This invention relates to game apparatus, 10 particularly of the type in which a plurality of balls are used to be struck by an impinging element.

A game such as billiards requires an expensive table and the use of expensive cues, 15 which places the game beyond the reach of a person with average means except in public places where the tables may be engaged by paying a certain rental or charge. Also, in the game of billiards, the force with 20 which the ball may be hit is usually limited as the cue is moved in the direction of impact and the player has to move his hand the full distance that the tip travels in hitting the ball. Moreover, by reason of the 25 necessity of guiding the cue over a fixed guide, the stroke of the cue is necessarily limited to a substantially straight line, and it is practically impossible to describe a curved path with the tip of the cue as the 30 ball is hit. In making the shots also the player has to assume a stooping, tiresome position which is very fatiguing, to a person who is not accustomed to it, after a comparatively short period of play.

35 The present invention has for its principal objects to provide a game which is as enjoyable as billiards and is free from the disadvantages above stated.

The game consists essentially of a platform 40 which may be placed on a parlor floor and leveled on which the balls are rolled by a mallet having a tip like that of a cue. The handle of the mallet is of such a length that the player can stand in an easy, upright 45 position, and the platform is lined with such material that the player can step on it when necessary to get into the best position to make a shot. The balls can be hit with great force by a slight movement of the 50 wrist, and it will be readily seen that the tip of the mallet can be swung a considerably greater distance than the hand of the player moves. Also the head of the mallet being 55 free, the cue ball may be hit with a greater variety of strokes than is possible in the ordinary game of billiards.

Further objects and advantages consisting in the novel arrangement and construction of the parts will more fully appear from the detailed description and the features 60 of novelty will be particularly pointed out in the claims.

In the accompanying drawing illustrating this invention, Figure 1 is a perspective view illustrating the platform in position 65 upon the floor and the player in position of making a shot. Fig. 2 is an elevation of the improved mallet. Fig. 3 is a detail view in sectional elevation, partly broken away, illustrating the preferred construction 70 of the platform, cushion and the leveling means. Fig. 4 is a fragmental detail plan view of one of the corners of the platform. Fig. 5 is a section taken along line 5-5 of Fig. 4.

Referring particularly to Fig. 1, the game is played upon a platform having a floor portion, designated generally as 10, inclosed by vertical walls 11, on which are mounted the resilient cushions 12, from which the 80 balls 13 are reflected as in the ordinary game of billiards. The player, however, stands erect and hits at the desired ball with a mallet 14 of a sufficient length to enable the player to reach the ball without stooping. 85 Whenever found necessary, the player may step with one or both feet upon the floor 10 of the platform to make the desired shot. Generally, it will be found convenient for the player to assume a position at which he 90 can sight along the line from the mallet ball to the next ball to be struck by the same.

The mallet itself has a handle 15 of a length preferably about two and one-half feet, such as would suit the average height 95 of player and a double faced head 16, tapering down to tips 17, corresponding to the tip of a cue now used in billiards. With this mallet, a great variety of shots can be made such as the "English", the "draw" 100 and a number of shots which are not possible in the ordinary game of billiards, such as a swinging shot for giving the ball greater curve than can now be obtained and also very fast shots and the like.

The game is particularly adaptable for indoor—even parlor use, and the various parts of the apparatus are made of such inexpensive construction that the game is within reach of people of moderate means. The 110 platform thus consists of a series of boards 18 and 19 laid crosswise with respect to

each other, forming a double flooring which is strong and stiff and will maintain its level surface without warping. At the edges, the platform is reinforced on the bottom by flat 5 steel bars 20, secured to the wood by suitable screws 21. Inclosing the platform and forming the supports for the cushions which reflect the balls are the rails or walls 11 secured in a suitable manner to the floor as 10 by means of nails 23 and are united at the corners by steel plates 24 secured by suitable screws 25.

I will now describe the improved cushion which combines the advantageous features 15 of low cost as well as great resiliency. Formed in the interior of the rails or walls 11 is a groove 7 of substantially semi-circular cross section. Against this groove is held a rubber tube or pipe 8 having a metal 20 tube or pipe 9 as its core. The rubber tubes and cores are preferably cut off at 45° at the corners to meet at right angles, as appears in Fig. 4. This meeting point may be finished off at the interior by the corner 25 pieces 260 which are preferably shaped so as to embrace the tubes, but of such dimensions as not to interfere with the proper contact of the ball with the cushions at the corners (Fig. 4). Into the metal tube forming 30 the core of the cushion are threaded the screws 27 passing freely through the rails 11. Thus, when the ball impinges against the cushion as shown in Fig. 3, the entire cushion is actuated bodily inward, thus obtaining 35 the resilient action both of the exterior and interior portion of the tube.

It will be noted in Fig. 3, that the head of the screw 27 is momentarily shifted away from the rail under the force of the impact 40 of the ball. This bodily movement of the cushion is very advantageous as the resiliency obtained thereby affords the most perfect reflection of the ball. This will be readily apparent as it will be noted that the side 45 of the tube nearest the ball will be compressed so as to form a slight dent therein which interferes slightly with the perfect reflection. However, the bodily movement of the cushion merely gives rise to the inwardly directed force which reflects the ball 50 according to the laws of perfect reflection.

For leveling the platform, the following means is provided: Passing through the rails adjacent the corners are leveling screws 55 28 threaded in the iron bar 20. When it is desired to level the platform, these screws are turned first on one side to level the platform in one direction and on the other side to level in the other direction, whereupon the 60 platform will be adjusted the desired degree. In case it should be found that there is any warping which would interfere with the perfect leveling of the platform, lag screws 29 disposed at the corners may be 65 utilized for screwing the corners of the plat-

form down to the floor or some other support which may be provided for that purpose. This may be done especially in public places where the game is to be permanently installed.

Any suitable material may be used for covering the floor of the platform so as to 70 secure the most perfect travel of the balls as well as being durable in use. Preferably, I use a covering of linoleum or a rubber 75 composition 30, or some other material having the required properties.

From the foregoing description, it will be understood that I have provided a new game 80 which is based on the principle of billiards, but still has certain characteristics all of its own in the manner in which it is played and the paraphernalia used. The game is much 85 more suitable for young and old than billiards by reason of the fact that it is played on a platform on which the player may step to reach any portion thereof and the use of a mallet instead of a cue is much more beneficial, as the positions and movements assumed by the player are freer and 90 less strained. The paraphernalia, moreover, are comparatively inexpensive and thus within the reach of persons of average means. The various parts are made so as to 95 promote durability and efficiency as will be evident from the foregoing description.

Having thus described my invention, I claim as new and desire to secure by Letters Patent:

1. As a new article of manufacture, a 100 game apparatus comprising a platform having marginal rails upstanding therefrom, a cushion at the interior of the rails, said cushion comprising an elastic tubular member, a comparatively inelastic core member, and 105 means for attaching the cushion to the rails.

2. As a new article of manufacture, a game apparatus comprising a platform having marginal rails upstanding therefrom, a cushion at the interior of the rails, said 110 cushion comprising an elastic tubular member, a comparatively inelastic core member, and means engaging the rails and the core member for attaching the cushion to the rails.

3. As a new article of manufacture, a game apparatus comprising a platform having marginal rails upstanding therefrom, a cushion at the interior of the rails, said cushion comprising an elastic tubular member, a comparatively inelastic core member, and attaching and guiding means passing 120 freely through the rail engaging the cushion whereby the latter is free to move bodily toward the rail under the impact of a ball. 125

4. As a new article of manufacture, a game apparatus comprising a platform having marginal rails upstanding therefrom, said rails being provided with a slot at the interior thereof, a cushion held in said slot, 130

said cushion comprising an elastic tubular member, a comparatively inelastic core member, and attaching and guiding means passing freely through the rail engaging the 5 cushion whereby the latter is free to move bodily toward the rail under the impact of a ball.

5. As a new article of manufacture, a game apparatus comprising a platform having marginal rails upstanding therefrom, a cushion at the interior of the rails, said cushion comprising an elastic tubular member, a comparatively inelastic core member, attaching and guiding means passing freely 10 through the rail engaging the cushion whereby the latter is free to move bodily toward the rail under the impact of a ball, and interior corner pieces facing the junction of the cushions.

15 6. As a new article of manufacture, a game apparatus comprising a platform having marginal rails upstanding therefrom, a cushion at the interior of the rails, said cushion comprising an elastic tubular member, a comparatively inelastic core member, attaching and guiding means passing freely 20 through the rail engaging the cushion whereby the latter is free to move bodily toward the rail under the impact of a ball,

25

and reinforcing plates and interior corner 30 pieces for the meeting ends of the rails and cushions.

7. As a new article of manufacture, a game apparatus comprising a platform having marginal rails upstanding therefrom, a cushion at the interior of the rails, said cushion comprising an elastic tubular member, a comparatively inelastic tubular core member, and attaching and guiding means passing freely through the rail engaging 40 the cushion whereby the latter is free to move bodily toward the rail under the impact of a ball.

8. As a new article of manufacture, a game apparatus comprising a platform having marginal rails upstanding therefrom, a cushion at the interior of the rails, said cushion comprising an elastic tubular member, a comparatively inelastic core member and screws passing freely through the rail 45 and threaded into the tubular core member.

Signed at New York city in the county of New York and State of New York this 15th day of June A. D. 1914.
